Term of patent 14 years

Int. Cl. D12—15

U.S. Cl. D12—142

The figure is a perspective view of a tire showing our new design, it being understood that the tread design is repeated throughout the circumference of the tire, as shown schematically by solid lines, the opposite side being substantially the same as that shown.

We claim:

The ornamental design for a tire, substantially as shown and described.
